UNITED STATES PATENT OFFICE.

LOUIS G. MERRITT, OF LOCKPORT, NEW YORK.

LATHE.

SPECIFICATION forming part of Letters Patent No. 699,547, dated May 6, 1902.

Application filed July 30, 1901. Serial No. 70,205. (No model.)

To all whom it may concern:

Be it known that I, LOUIS G. MERRITT, residing at Lockport, in the county of Niagara and State of New York, have invented certain new and useful Improvements in Lathes, of which the following is a full, clear, and exact description, such as will enable others skilled in the art to which it appertains to make and use the same.

10 My invention relates to the general type of machine in which a piece of stock, wood, or otherwise to be operated on is held between chucks in a lathe, the tools for operating upon said stock being carried by a carriage or carriages adapted to be moved transversely of the line of centers of the chucks holding such work. I show a construction designed especially for use in a veneer-cutting machine; but my invention is capable of use in other 20 relations.

The objects of my invention are to provide a new and improved construction of the framework of the lathe or veneer-cutting machine in which injury and wear due to the strain 25 resulting from use will be reduced to a minimum; to provide a new and improved construction wherein the dogging nut or nuts which control the longitudinal movement of the spindle will be easily accessible for purposes of oiling and within the reach of an operator standing near the center of the machine; to provide a construction in which the ways upon which the slide-blocks of the carriage work may provide bearings for such 30 slide-blocks both above and below the line of centers; to provide a construction wherein the feed-screws for the knife-carriage apply their pressure on the line of centers; to provide improvements in the manner of driving the various feed-shafts of the machine and in the arrangement of such shafts; to provide a construction wherein the spindles or chuck-shafts are supported at a point outside the heads of the frame, as well as within said 45 heads.

My invention consists, further, in certain features of construction and combinations of elements, the objects and advantages of which will hereinafter appear and the novel features 50 thereof pointed out in the claims at the end of this specification.

The invention is clearly illustrated in the

accompanying drawings, which, with the characters of reference marked thereon, form a part of this specification, and in which— 55

Figure 1 is a side elevation of my machine as a whole, the feed-shafts for the slide-block in the left end being in section and the knife-carriage being omitted. Fig. 2 is a longitudinal vertical section through the center of 60 the machine. Fig. 3 is a transverse vertical section on line 3 3, Fig. 1. Fig. 4 is a sectional elevation taken on the line 4 4, Fig. 1, looking toward the right. Fig. 5 is an end elevation looking toward the left of Fig. 1. 65 Figs. 6 and 7 are sectional details of quick-feed wheels and locking and controlling devices therefor adapted to be used in connection with the spindles. Fig. 8 is a sectional view, partly in elevation, showing an auxiliary carriage located on the opposite side of the line of centers from the main carriage, together with the various shafts by which said auxiliary carriage and the main carriage are 70 driven. Fig. 9 is a detail view, partly in section and partly in elevation, showing the ways and slide-blocks for the auxiliary carriage, together with an impression-roll carried thereby. Fig. 10 is a side elevation, with parts broken away, showing the position of the 75 knife with relation to the line of centers.

Similar reference characters refer to similar parts throughout the several views.

Referring now more particularly to Figs. 1 and 2, it will be understood that for purposes 85 of illustration the distance between the chucks has been shown somewhat less than it would be in the actual machine, but that such difference is a matter purely of design in the construction of the framework, of 90 which the main frame (designated in a general way by A) is cast in one piece and comprises a base portion B and end or head portions C C integral therewith. For convenience of description parts will be spoken of 95 throughout the specification as "castings;" but this is not a term of limitation, as such parts may be produced in any desired way. Uprights or supports D D are separate from the main frame, but bolted thereto adjacent to 100 and parallel with the inner faces of the head portions. Except as otherwise stated, the parts on one side of the machine are duplicates of those on the other, and a description

of the support, spindle, and associated parts on one side of the machine will be taken to apply to those on the other, the points of difference, where there are such, being particularly pointed out. Chuck-spindle 1 has a bearing in the end or head portion of the frame C, as is usual, and also a second bearing independent of such head in the support D. This bearing surrounds the chuck-spindle 1 and a short sleeve 2, through which the spindle passes.

3 is a spindle-cap. It will be seen that the construction is such that the spindle 1 is free to pass through the short sleeve 2, held by the support D, without applying sidewise pressure to such support. This chuck-spindle or main driving-spindle 1, which carries at its end the chuck 4, is threaded for a large portion of its length and is carried within the long sleeve 5, which is revolved in the bearings 6 in the head portion C by means of large gear-wheel 7, keyed onto the outside end of the sleeve 5.

The counter-shaft of the machine (indicated at 30) is supported in suitable boxes and caps and driven from a suitable source of power. Pinions 31 31 engage and drive the gears 7 on the ends of the chuck-spindles. The spindle and sleeve revolve together on account of a long feather and feather-way common to both, as in well-known constructions; but the spindle is free to move through the sleeve lengthwise, which longitudinal movement is necessary in dogging the log. A cylindrical nut 8 on the spindle 1 is placed between the sleeve 5 and the bearing in the support D, which will be spoken of as bearing d. A hand-wheel 9 on nut 8 is adapted to control the rotation of such nut. In order to provide for the longitudinal movement of the two chuck-spindles 1, hand-wheel 9 is shown at the right hand of Fig. 2, while upon the left-hand spindle is a quick-feed wheel 10, double-rimmed, as at 11 and 12, having proper devices for acting upon either rim in order to rotate said wheel in one direction or the other, as will be hereinafter fully described. Caps 13 13 hold the chuck-spindles to the bearing in the head portions of the frame.

I provide the following construction for obtaining a quick rotation of the dogging-nut in either direction in order to give a quick longitudinal movement to the chuck-spindle on the left-hand end of the machine. A sleeved support 15 carries the inner sleeve 16. Friction-shaft 18, eccentrically mounted in such sleeve, carries on its end paper frictions or frictional rolls 19 and on the other end friction-pulleys 20, the position of the paper frictions being controlled by the lever 21, connected to sleeve 16, so that the revolving friction-roll 19 can be brought into contact with either the inner or the outer rim of the double-rimmed wheel 10, and thus a rapid rotation of said wheel and the dogging-nut is se-

cured. As will be seen upon inspection of Fig. 1, the lever 21 is connected through a slot in the sleeved support 15 to the inner sleeve 16, in which the shaft 18 of the paper frictions is eccentrically mounted. Accordingly by turning the sleeve 16 within its support by means of said lever the position of the paper frictions can be varied at will. The same construction is shown in detail in Fig. 75 as used for rotating the main feed-shaft F. This device is well known; but in connection with the quick feed on each end of the machine is likewise a device for positively locking said wheel, which device will now be described.

A bracket 21 (shown in Fig. 2) carries a shaft 22, which is flattened at its end, as shown at 23 in Figs. 4 and 6, where it bears between two friction-shoes 24 24, carrying friction-woods 25 25, adapted to bear one against the inner face of the rim and the other against the hub of the hand-wheel 9. By means of lever 26 on the end of the said shaft 22 this shaft can be rocked, whereupon the friction-woods will be forced against the adjacent parts of the hand-wheel 9 to lock it from rotation. The locking device in connection with the wheel 10 is similar in all respects, except that the friction-woods bear 95 against the inner and outer rims, as shown in Fig. 6.

Referring now to Figs. 1, 4, and 10, the construction of the slide-blocks which support and carry with them the tool-carriage of the machine will be described.

It will be understood that the tool-carriage or tool-carriages may comprise any suitable devices for operating upon the stock carried between the chucks. In a veneer-cutting machine this tool-carriage would comprise a knife-carriage proper and means for supporting the pressure-bar. Such a construction is illustrated in Fig. 10, where a knife-carriage 80 and pressure-bar 82 are shown in their proper relation to the frame. The knife-carriage 80 has side plates 81, which are mounted in a suitable manner upon the slide-blocks 41, so that the knife-carriage is fed with the slide-blocks. The construction 115 of knife-carriage and pressure-bar shown herein is illustrated and described more fully in my pending application, No. 64,374, filed June 13, 1901. Further illustration or description thereof is not deemed necessary in this case. The knife-carriage is illustrated in connection with the chuck-spindles and slide-blocks in order to show the advantage of a construction in which the edge of the knife is substantially on the line of centers 125 and on the line of feed, so that the strain upon the knife will be absorbed by the carriage in the most efficient manner, this being particularly the case, because the ways for the heavy knife-carriage furnish supports therefor both above and below the line of chuck-centers, and the feed-screws point to the centers of

the chuck-shafts. The supports D furnish ways 40 for the slide-blocks of the carriage, (indicated at 41.) These ways have bearings for the slide-blocks both above and below the line of centers, gib 42 being placed on the upper side of said ways. The feed-screws 43, which actuate the slide-blocks, pass through boxes 43', attached to said blocks, and are so located that they apply their pressure in a direct line 5 with the main drive-spindles and the edge of the knife. At the outer end of the feed-screw 43 is a spur-gear 44, meshing with the spur-gear 45 on the end of the second shaft 46, which passes through the cap 47 in the support D and 10 carries a bevel-gear 48, meshing with a bevel-gear 49 upon the vertical shaft 50, which in turn is driven by the bevel-gear 51 from the bevel-gear 52 upon the main feed-shaft F. It will be seen that this construction permits the 15 shaft 46 to pass beneath the spindles, and it is thus adapted to be threaded and to actuate a second carriage on the other or back side of the machine, as viewed in Fig. 1. Such second carriage is shown in position in 20 Figs. 8 and 9, wherein are shown ways 100, adapted to be bolted or otherwise secured to the base of the machine, upon which ways are reciprocable slide-blocks 101, provided with feed-nuts 102, coöoperating with the 25 threaded ends of the feed-screw shafts 46. These slide-blocks carry boxes or bearings 103 for the journals of an impression-roll 104. These boxes are held to the slide-blocks by gib 105 and adjustable by means of the screw-shafts 106. Instead of the roll a plate-casting 30 could be mounted upon the carriage for the purpose of holding chamfering or marking knives, and other obvious variations will present themselves.

35 The novel feature claimed herein resides in the construction such that it is possible to use a threaded shaft 46 to drive an auxiliary carriage or, when the auxiliary carriage is not desired, to use such threaded shaft merely as an element of the construction for driving the feed-screw 43 from the driving-shaft F. It will be obvious also that, if desired, at such times the long shaft 46 may be replaced by a short shaft which shall carry gears, such as 40 45 and 48, thereby connecting gear 49 with gear 44. From this viewpoint the shaft 46 is something more than a mere supplementary shaft provided to drive a second carriage. It is a part of a system of shafting devised, in 45 the first place, to operate the knife-carriage with a pressure properly applied; second, to operate a second carriage conjointly with it; third, to transfer the motion in such a way that the working parts offer no obstruction to free 50 access to the center of the machine; fourth, to provide a compact design wherein the friction-wheel and feed-gears that actuate the main driving-shaft F are carried close to the main frame, to which they are thus easily and rigidly attached. By introducing the shaft 46 the shaft 50, which drives it, is placed well toward

the center of the machine, whereas if the shaft 50 connected 43 directly with the long shaft F the latter would have to be out on the floor, where the operator would be compelled to step 55 over it. Other advantages will be obvious. In similar devices old in this art no such construction is possible. Feed-shaft F is supported in suitable brackets on the framework and is driven at one end by the quick-feed 60 device heretofore described in connection with the same device upon chuck-spindle 1 and shown in detail in Fig. 7, by which it may be given a quick rotation in either direction. At the right hand of said shaft it is 65 driven through the interposition of a proper clutch g by a spur-gear 70, meshing with the gear 71 on the end of the feed-shaft. Gear 70 is on one end of a short sleeve 72, supported on an arbor k. On the other end of 70 said sleeve is a sprocket-wheel 53, which is connected by a chain 54 to a sprocket-wheel 55 (shown in section at the right of Fig. 2) on the end of the sleeve 5 at the left-hand end of the machine. Arbor k is supported from 75 the end of a long arm 56, which is pivotally mounted upon sleeve 5, just outside of the sprocket-wheel 55, and carries a bolt 57, which passes through an elongated slot 58 in a curved link 59, bolted to the framework at 80 85 60 and 61, so that by loosening the bolt 57 the arm 56 can be swung upward, bolt 57 passing along the elongated slot, and the gear 50 disengaged from the gear 51 or proper adjustment secured. The operation, which will 90 now be readily understood, is as follows:

The feed-shaft F may be given a quick rotation from the quick-feed wheel to carry the tool-carriage, which is driven therefrom through the feed-shafts 43 quickly toward or 95 from the work, and by throwing in the clutch g the cutting-feed, which is driven from the main driving-shaft through the gears 31, gear 7, sleeve 5, sprocket-wheels, chain, and gears 50 and 51 on the left-hand end of the machine, may then be put in operation in order 100 to supply a constant cutting-feed for the tool-carriage. In dogging the log, in releasing the core, or in moving the core bodily the spindles 1 may be moved in the desired direction by rotating the hand-wheel or fast-feed wheel in the same direction in which the spindles are rotated, but more rapidly, or by 105 rotating such wheels in a different direction or when great power is desired, as to finish 110 driving a chuck into the log, the dogging-nuts, one or both, may be locked positively by movement of the lever or levers 26, thereby throwing the friction-woods 25 against the wheel-rims, as heretofore described. The 115 further operation will be apparent to one skilled in the art from the description of various parts and need not be elaborated.

The advantages of my construction result, 120 in the first place, from making the main frame integral and separate from the supports D in ways upon which the knife-carriage slides.

The strain which comes upon the machine from dogging the log is entirely lengthwise. This strain is, in the first place, resisted by a casting in one piece without joints and is, in 5 the second place, not in the least applied to the ways D, tending to spread them apart. Where these ways are integral with the main heads or ends of a veneer-machine or where they are bolted to these ends, the dogging 10 strain forces the ways apart and gives the knife-carriage too much play. In my construction the strain is applied to the bearings 6 at a point where the shoulder a makes a thrust-bearing, as at a'. As the support D is provided 15 with a bearing d, which surrounds the spindle 1 and sleeve 2, the strain which comes from the action of the pressure-bar is transverse or at right angles to the dogging strain, and the support or way casting D retains within it 20 itself a large amount of the strain which would otherwise come entirely upon the main bearing 6. Thus each set of strains is provided for independently of the other and by means of parts cast in one piece without joints. 25 The introduction of the extra bearing d in the support D gives an opportunity to place the dogging-nut 8 between this bearing and the main bearing 6 in the end or head portion of the frame. When the spindle is being 30 thrust into the log, the pressure is between the nut and the main bearing 6, and when being withdrawn from the log the pressure is between the nut and the way-bearing d. In constructions which are old in the art 35 the dogging-nut is carried within a flanged casting bolted or screwed to the opposite nut of sleeve 2. This brings the nut and its controlling devices outside the drive-gear and at the extreme end of the machine. The case 40 covers the nut from view, so that any injury due to the bearing strain is unnoticed and much trouble is caused. The construction is also liable to breakage, depending as it does on bolts and screw-threads to maintain it. In my construction the nut 8 is close 45 to the center of the machine, and its controlling devices are handy to the operator. There are no bolts or screw-threads to hold the nut in place, and it is open to inspection at all 50 times.

In constructions common in the art but one track or way, and that below the line of centers, is provided for the knife-carriage, and a gib is placed underneath the track. In my 55 construction bearing surfaces or tracks both above and below the center of the spindles are provided for the support of the slide-blocks for the knife-carriage, and the feed-screws apply their pressure in a direct line 60 with the main drive-spindles. While the feed-screws 43 are so geared that they run directly to the center of the drive-spindle, the construction is such that the parallel shafts 65 may pass below the spindles to the back of the machine, where they may be threaded and operate a second carriage on the back

side of the log. This arrangement also allows the horizontal feed-shaft F to be located forward, permitting the operator to get up close to the log, while in constructions old in 70 the art this shaft is vertically in line with the spur-gear at the outer ends of the main feed-screws.

The advantages resulting from the construction in which I provide a positive frictional lock in connection with the dogging-nuts, so that when great power is needed these dogging-nuts may be held against rotation without being obliged to use the pawl-and-ratchet construction, which is old in the 80 art and which results in great strain and shock to the machinery, are obvious.

Having described my invention, what I claim as new, and desire to secure by Letters Patent, is—

1. In a veneer-cutting machine, a carriage for supporting the veneer-cutting knife, and supports providing ways for said carriage, said ways furnishing bearings for said carriage both above and below the line of chuck 90 centers, the construction and arrangement being such that the cutting edge of the knife is located substantially on the line of feed and in the plane of the chuck centers.

2. In a veneer-cutting machine, in combination with the usual chucks and chuck-spindles, a carriage for the veneer-knife reciprocable with relation to said chucks, ways for said carriage furnishing bearings therefor both above and below the line of chuck centers and feed-screws located on the line of chuck centers, whereby the strain upon the veneer-cutting knife is substantially along the line of the feed-screws.

3. In a veneer-cutting machine, a main frame, bearings in said main frame for the chuck-spindles, supports located on said main frame adjacent the head portions thereof, ways on said supports for the slide-blocks, which support the veneer-knife carriage, said ways furnishing bearings for said slide-blocks both above and below the line of chuck centers, bearings in said supports through which the chuck-spindles pass, and feed-screws for said slide-blocks, said feed-screws being located so as to apply their pressure in the line of centers.

4. In a veneer-cutting machine, a frame comprising a base portion and two head portions, in combination with supports located parallel to the inner faces of said heads and connected to said base portions, bearings in said head portions for the chuck-spindles, supplementary bearings in said supports for the chuck-spindles, ways in said supports, said ways furnishing bearings for the slide-blocks of the veneer-cutting-knife carriage both above and below the line of centers of the chucks, whereby the strain upon the veneer-knife in operation will be divided between the two ways, substantially as and for the purposes set forth.

5. In a veneer-cutting machine, a main

frame, ways upon said main frame adapted for slide-blocks for a main carriage, feed-screws for said slide-blocks acting in the line of centers, threaded shafts below said feed-screws and parallel therewith, which shafts pass below the drive-spindles and are adapted to act as feed-screws for an auxiliary carriage, means for driving said feed-screw shafts from said second shafts, and means for driving said second shafts from the main feed-shaft of the machine.

6. In a veneer-cutting machine, in combination, with the usual chucks and chuck-spindles, a main carriage, a feed-screw therefor, a shaft passing below said chuck-spindles, and gearing at one end with said feed-screw and threaded at its other end whereby it is adapted to engage the feed-nut of an auxiliary carriage located on the opposite side 20 of the line of centers from the main carriage.

7. In a veneer-cutting machine, in combination, with the usual chucks and chuck-spindles, a main carriage, a feed-screw therefor, a shaft passing below said chuck-spindles, and gearing at one end directly with said feed-screw and threaded at its other end whereby it is adapted to engage the feed-nut of an auxiliary carriage located on the opposite side of the line of centers from the main 25 carriage.

8. In a veneer-cutting machine, a tool-carriage supported upon slide-blocks in suitable ways, feed-screws for said slide-blocks, gears connecting said feed-screws with shafts parallel therewith, a driving-shaft F located at a substantial distance within the ends of said feed-screws and auxiliary shafts and toward the center of the machine, and gearing between said driving-shaft and said auxiliary 35 shafts, substantially as and for the purposes set forth.

9. In a veneer-cutting machine, in combination, a tool-carriage supported upon slide-blocks in suitable ways, feed-screws therefor, 40 parallel shafts geared directly to said feed-screws and extending toward the center of the machine, a driving-shaft located at a substantial distance within the ends of said feed-screws and toward the center of the machine, 45 and driving connections between said shafts.

10. In a veneer-cutting machine, in combination, a frame comprising a base portion and head portions integral therewith, chuck-spindles having bearings in said head portions, an independent way or support located 50 adjacent one of said head portions and providing supplementary bearings for one of said spindles and a way for the slide-block of a tool-carriage, a nut located upon said spindle 55 between said head portion and said support, means for rotating said spindle, and means for independently controlling the rotation of said nut, the construction and arrangement being such that the strain resulting from the 60 dogging of the work is borne by the head portion

of the frame while the strain resulting from the action of the tool-carriage is borne in the first instance by said support.

11. In a machine of the character described, a frame comprising a base portion and head portions, supports located on said base portion adjacent the inner faces of said head portions, ways in said supports adapted for the slide-blocks of a tool-carriage, spindles supported in bearings in said head portions and 70 in said supports, nuts controlling the longitudinal movement of said spindles located between said head portions and said supports, whereby the strain resulting from the dogging of the work is borne by the head portion 75 of the frame, while the strain resulting from the action of the tool-carriage is borne in the first instance by the supports.

12. In a veneer-cutting machine, in combination, a frame having the base portion B 80 and the integral head portions C C, a support or way D, a spindle 1 supported in bearings in one of said head portions and in such way, a nut 8 upon such spindle located between said support and said head portion, 85 means for driving said spindle, and means for controlling the rotation of said nut independently of said spindle.

13. In a veneer-cutting machine, in combination, a frame, suitably-driven spindles supported upon said frame, suitable ways upon said frame, slide-blocks in such ways, feed-screws 43 for such slide-blocks, a second shaft 46 from which shafts 43 are driven, shaft 50 from which said shafts 46 are driven, and a 90 main feed-shaft F from which said shaft 50 is driven, the construction and arrangement being such that the main feed-shaft F is inside of the vertical plane of the end of the shaft 43. 95

14. In combination, a lathe-spindle, a nut controlling the longitudinal movement of said spindle, and power-actuated frictional means for locking said nut from rotation.

15. In combination, in a machine of the character described, a lathe-spindle, a nut controlling the longitudinal movement of said spindle, a wheel connected to said nut to rotate therewith, and a frictional device located within the rim of said wheel on said wheel 110 whereby said nut may be prevented from rotation. 115

16. In combination, a lathe-spindle, a nut controlling the longitudinal movement of said spindle, a rimmed wheel keyed to said nut, 120 friction-shoes adapted to bear within the rim of said wheel, and means for forcing said shoes against said rim whereby the wheel will be held from rotation.

17. In combination, a lathe-spindle, a nut 125 controlling the longitudinal movement of said spindle, a rimmed wheel keyed to said nut, friction-shoes adapted to bear one against the inner face of said rim and one against the hub of said wheel, a flattened shaft upon 130

which the sides of said shoes normally rest, and means for rocking the said shaft whereby the said shoes will be forced against the adjacent parts of said wheel and said wheel 5 will be locked against rotation.

18. In a veneer-cutting machine, in combination, the threaded spindle 1, nut 8 upon said spindle, wheel 9 carried with said nut, friction-woods 25 and friction-shoes 24 adapt-

ed to bear within said wheel, flattened shaft 10 22 controlling the position of said friction devices, and lever 26 for rocking said shaft.

In testimony whereof I affix my signature in the presence of two witnesses.

LOUIS G. MERRITT.
